Henry Whitney

United States Patent Office.

HENRY WHITNEY, OF EAST CAMBRIDGE, MASSACHUSETTS.

Design No. 4,021, dated May 10, 1870.

DESIGN FOR A LAMP-FOUNT.

The Schedule referred to in these Letters Patent and making part of the same.

To all whom it may concern:

Be it known that I, HENRY WHITNEY, of East Cambridge, in the county of Middlesex and State of Massachusetts, have invented a Design for a "Lamp-Fount," of which the following is a full, clear, and exact description, reference being had to the accompanying photograph forming part of this specification.

A represents a receptacle, of cylindrical form, from *a* to *b*, at each of which points the outside of the receptacle is surrounded by a circular band or ring, *c*, between which is formed a series of figures, *d*, composed of a combination of segments of curves of the shape shown, the figures being oblong in a horizontal direction, that is to say, the distance between the extremities of a figure measured outside the surface of the cylinder in a plane passing horizontally through it, is greater than that measured in a line passing vertically through its other extremities.

These figures are in bas-relief, and are separated from each other by vertical bars or projections *e*.

The top of the cylindrical portion *a b* is surmounted with a dome-shaped roof, the center of which is left open, and surrounded by a circular neck or flange, *B*, for the reception of the collar, to which the burner is to be attached.

The bottom of this cylindrical portion *a b* terminating in a central pin or projection, *f*, of suitable form to fit into the socket of the stand which supports the "fount."

Claim.

What I claim as my invention, and desire to secure by Letters Patent, is—

The design for a "lamp-fount," substantially as herein shown and described.

In testimony whereof I have hereunto set my hand this 24th day of March, 1870.

HENRY WHITNEY.
